UNITED STATES PATENT OFFICE.

WILLIAM H. DAVIS, OF BRONXVILLE, AND FREDRICK E. JOSS, OF BROOKLYN, NEW YORK, ASSIGNORS TO LEKTOPHONE CORPORATION, A CORPORATION OF DELAWARE.

TONE-CONTROL DEVICE FOR TALKING-MACHINES.

1,316,536.

Specification of Letters Patent. Patented Sept. 16, 1919.

Application filed May 9, 1918. Serial No. 233,467.

To all whom it may concern:

Be it known that we, WILLIAM H. DAVIS and FREDRICK E. Joss, both citizens of the United States, residing at, respectively, 5 Bronxville, county of Westchester, State of New York, and borough of Brooklyn, county of Kings, city and State of New York, have invented certain new and useful Improvements in Tone-Control Devices 10 for Talking-Machines; and we do hereby declare the following to be a full, clear, and exact description of the invention, such as will enable others skilled in the art to which it appertains to make and use the 15 same.

This invention relates to tone control devices for talking machines, and in particular for talking machines of the so-called Hopkins type, wherein the vibrations of the 20 stylus are transmitted by a connecting device to a conical diaphragm of large area, the connecting device comprising a rod or analogous element and a stylus holder. The diaphragm referred to is freely exposed to 25 unconfined air and is so constructed and arranged as to take the place of the usual sound-box and of its associated horn or similar amplifier.

In instruments of the character stated, 30 the diaphragm is carried by a supporting bar, which is mounted to swing across the record and is provided with a bore that extends from end to end thereof; said bore receiving the vibration transmission 35 connections, the rod element of which is joined at its rear end to the apex of the diaphragm and at its front end to the stylus holder, the latter being fulcrumed on the front end of the aforesaid bar and disposed partly within the same. It follows, 40 therefore, that the stylus, in traveling along a phonic line, will impart to the diaphragm vibrations corresponding to those recorded in said line, so that the intensity of the vibrations of the diaphragm 45 is dependent upon that of the vibrations passing through or set up in the transmission connection. Consequently, if some means be provided whereby the vibrations 50 of the transmission connection can be damped, the vibrations of the diaphragm, and, hence, the tone of the instrument will be correspondingly affected, and will be diminished or increased according as the damp-

ing action exerted upon the transmission connection is increased or decreased.

The present invention aims, therefore, to provide an effective means or device for acting upon the transmission connection in the manner indicated, such action being obtained, according to the illustrated embodiment of the invention, by disposing a pair of jaws on opposite sides of the said connection so as to grip the latter when moved toward each other, the operation of the jaws being produced by a device which is rotatably mounted upon the support.

The accompanying drawing represents one form which the invention may take in practice; but it is to be understood that no limitation to the precise structural details thereof is intended nor to be imposed, since modifications of and changes in such disclosure may obviously be made without departing from the scope of the invention as subsequently claimed.

In said drawing:

Figures 1 and 2 are, respectively, a vertical and a horizontal fragmental longitudinal sectional view showing the application of the invention to the supporting bar of a Hopkins-type machine.

Fig. 3 is a transverse section, taken on line 3—3, Fig. 1;

Fig. 4 is an end view of the main operating element;

Fig. 5 is a perspective view of one of the jaws; and

Figs. 6 and 7 are detail views of certain adjuncts of the clamping jaws.

Referring more particularly to the mechanism illustrated in the aforesaid drawing, 10 indicates generally a swinging support or bar which is mounted to move across the record or its equivalent and is provided with a bore 11 that extends through it from end to end. The bore 11 receives the transmission rod 12, which, as previously stated, forms one element of the transmission connection, the latter also comprising the stylus 10 holder 13. The rod 12, as usual in Hopkins machines, projects beyond the ends of the bore 11 and is connected at its rear end to the apex of the conical diaphragm, (not shown), and at its front end to the stylus holder 13, the said holder being connected, in turn, with the front end of the bar through the intermediary of a leaf spring.

14. None of these features forms any part of the present invention, however, and for that reason extended illustration and description thereof are omitted, it being deemed sufficient to state that the leaf spring 14 provides a resilient mounting for the stylus holder, and that the vibrations of the stylus carried by the holder are transmitted from the holder through the rod 12 to the 10 apex of the diaphragm in a manner to move the entire conical portion of the latter bodily. The leaf spring may be mounted in the rod end in any desired way, but is preferably capable of adjustment for the purpose of 15 varying the effective length of its exposed end,—that is, the portion of the spring between the bar end and the stylus holder.

The tone control device is carried by the supporting bar 10, and, in the construction 20 illustrated, is disposed within a transverse recess or chamber 15 which intersects the bore 11 of the bar, as represented in Figs. 2 and 3. Said device preferably consists, as stated above, of a pair of T-shaped jaws, 25 generally designated 16, which are arranged at opposite sides of the transmission rod 12 and are movable toward and from each other so as to grip or release said rod. The jaws proper are indicated at 17, and are shown as 30 integral parts of these T-shaped members, one of which is depicted in Fig. 5, the base pieces 18 of said members having reversely-threaded, central openings 19, through which passes an adjusting screw 20, formed 35 with left-and-right-hand threads, so that rotation of the screw in one direction or the other will cause the aforesaid jaws to approach or recede from each other. During this movement, rotation of the jaws is prevented in some suitable way, for example, 40 by means of transverse guides 21, which pass through openings 22 located in the bases 18 of the jaws at opposite sides of the screw openings 19, the screw and guides being supported at their ends in the top and bottom 45 walls of the recess 15. Each of the jaws proper is provided with a cover 23, (Fig. 6); which is preferably constructed of felt, though it may be made of leather or other 50 suitable material capable of damping the vibrations of the rod 12; these covers or facings being secured in place by screws or the like which pass through metal side plates 55 24, (Fig. 7), disposed against the up-turned side portions of said covers.

As will be understood from the foregoing, the movement of the jaws 16 is effected by the rotation of the adjusting screw 20. To produce such rotation, there is provided on 60 one end of the screw a gear 25, the latter meshing, in the present instance, with an annular row of gear teeth 26 formed on the reduced inner end of a sleeve 27, which rotatably encircles the supporting bar 10. The 65 toothed end 26 of this sleeve 27 extends with-

in and is protected by a sleeve 28, fixed on said supporting bar, the said sleeve 27 being held against lateral movement in one direction by a circumferential flange 29 provided on the bar and engaging a shoulder 70 30 formed by the reduction of the toothed end 26, and in the other direction by a second fixed sleeve 31 on said bar. The arrangement is such, therefore, that rotation of the loose intermediate sleeve 27 in one direction or the other, will effect a corresponding rotation of gear 25, and, hence, of the adjusting screw, with the result that the jaws 16 are caused to move toward or from each other according to the direction in 80 which said sleeve is turned. When said jaws grip or engage the transmission rod, the vibrations of the latter and, consequently, of the diaphragm will be damped, and the tone of the instrument will be decreased or softened, the extent of such decrease depending upon the extent or degree of the gripping action or engagement referred to. Similarly, when the adjusting screw is turned in a direction to move the jaws away 90 from the aforesaid rod, the transmission of the vibrations therethrough will be unimpeded, and the tone will increase in loudness until the maximum is reached.

Further description of the invention and 95 its mode of operation is believed to be unnecessary, and is, accordingly, omitted.

We claim:

1. The combination, with a tubular support, and a vibration transmission connection disposed therewithin; of a tone control device within said support operative upon 100 said transmission connection to damp its vibrations.

2. The combination, with a tubular support, and a vibration transmission connection disposed therewithin; of means within 105 said support to damp the vibrations of said transmission connection; and means rotatably mounted on said support for operating 110 said damping means.

3. The combination, with a tubular support, and a vibration transmission connection disposed therewithin; of means movably mounted within said support to damp 115 the vibrations of said transmission connection; and means mounted on the exterior of said support for operating said damping means.

4. The combination, with a tubular support, and a vibration transmission connection disposed therewithin; of a gripping device located interiorly of said support to 120 damp the vibrations of said transmission connections; and means for operating said 125 gripping device.

5. The combination, with a tubular support, and a vibration transmission connection disposed therewithin; of a gripping device located interiorly of said support to 130

- damp the vibrations of said transmission connection; and means rotatably mounted on said support for operating said gripping device.
5. 6. The combination, with a tubular support, and a vibration transmission connection disposed therewithin; of means within said support arranged to damp the vibrations of said transmission connection; and a 10 rotatable member encircling said support and connected to operate said damping means.
7. The combination, with a tubular support, and a vibration transmission connection disposed therewithin; of a pair of clamping jaws located within said support to engage said transmission connection from opposite sides thereof to damp its vibrations; and means for operating said jaws.
- 15 8. The combination, with a tubular support, and a vibration transmission connection disposed therewithin; of a pair of clamping jaws located within said support to engage said transmission connection from opposite sides thereof to damp its vibrations; and means rotatably mounted on the exterior of said support to operate said clamping jaws.
- 20 9. The combination, with a tubular support, and a vibration transmission connection disposed therewithin; of a pair of clamping jaws located within said support at opposite sides of said transmission connection to engage the same and thereby damp its vibrations; an adjusting screw in said support on which said jaws are mounted; and means for rotating said screw.
- 25 10. The combination, with a tubular support, and a vibration transmission connec-
- tion disposed therewithin; of a pair of 40 clamping jaws located within said support at opposite sides of said transmission connection to engage the same and thereby damp its vibrations; an adjusting screw to which said jaws are connected; a gear fixed to said 45 screw; and a toothed member on said support engaging said gear to rotate the same.
11. The combination, with a tubular support, and a vibration transmission connection disposed therewithin; of a pair of clamping jaws located within said support at opposite sides of said transmission connection to engage the same and thereby damp its vibrations; an adjusting screw to which said 50 jaws are connected; a gear fixed to said screw; and a sleeve rotatably fitted on said support and having an annular row of gear teeth engaging said gear to rotate the same.
12. The combination, with a support, and a vibration transmission connection carried thereby; of a pair of T-shaped clamping jaws engageable with said transmission connection from opposite sides thereof to damp its vibrations; an adjusting screw threaded through the bases of said jaws to move the latter in unison; means for rotating said screw; and guide means extending through said bases to hold the jaws against rotation during their movement.
13. The combination, with a tubular support, and a vibration transmission rod extending therethrough; of means disposed 70 interiorly of said support for engagement with said rod to damp its vibrations; and means for adjusting said damping means. 75

WILLIAM H. DAVIS.
FREDRICK E. JOSS.
